US0D1104596S

(12) **United States Design Patent** (10) **Patent No.:** **US D1,104,596 S**
(45) **Date of Patent:** **** Dec. 9, 2025**

(54) **COOKING DEVICE**

(71) Applicant: **SharkNinja Operating LLC**,
Needham, MA (US)

(72) Inventor: **Da Deng**, Newton, MA (US)

(73) Assignee: **SharkNinja Operating LLC**,
Needham, MA (US)

(**) Term: **15 Years**

(21) Appl. No.: **29/877,012**

(22) Filed: **May 31, 2023**

(51) **LOC (15) Cl.** **07-02**

(52) **U.S. Cl.**

USPC **D7/350.1**

(58) **Field of Classification Search**

(57) **CLAIM**

The ornamental design for a cooking device, as shown and described.

DESCRIPTION

FIG. 1 is a front perspective view of my cooking device;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The broken lines shown in the figures show features of the cooking device that form no part of the claimed design.

1 Claim, 8 Drawing Sheets
